UNITED STATES PATENT OFFICE.

DAVID R. JONES, JR., OF DUBUQUE, IOWA.

ACCOUNT-BOOK.

1,316,899.

Specification of Letters Patent. Patented Sept. 23, 1919.

Application filed May 24, 1918. Serial No. 236,294.

To all whom it may concern:

Be it known that I, DAVID R. JONES, Jr., a citizen of the United States, residing at Dubuque, in the county of Dubuque and 5 State of Iowa, have invented certain new and useful Improvements in Account-Books, of which the following is a specification.

This invention relates to instruments for keeping business accounts. Book-keeping 10 systems generally in vogue require as the physical instrumentalities or agencies for carrying them into effect a plurality of related books of account, such as day books, journals, ledgers and cash books, all of 15 which are posted by the book-keeper in keeping a record of the accounts, and all of which must be separately examined when making audits, or otherwise determining the financial condition of the business 20 to which they relate at any given time.

The work of posting and examining all of these books, especially in large businesses, is quite onerous and involves a considerable expenditure of time and labor. The principal 25 object of the present invention is to provide a novel means or instrumentality for keeping an accurate record of business accounts in mercantile houses, manufacturing establishments, professional offices, and any 30 and all other business establishments where the necessity or desirability of keeping financial records exists, which shall be simple and inexpensive in construction, readily understood by book-keepers and accountants, 35 easy to manipulate, and which shall possess the great advantage of enabling the condition of the business at any time, and in respect of any or all of its various departments, to be seen and ascertained practically 40 at a glance. Another object is to provide an instrument for keeping business accounts wherein the various functions of the several separate account books heretofore used may be combined in a single physically connected 45 or associated group of leaves or sheets of varying lengths and in superposed relation, which group may cover any fixed period of time, such as a day, a week, or a month, and wherein the totals or aggregates of individual 50 items or departments shown by preceding similar groups since the first of the business year, or any other fixed starting point, may appear at the foot of the sheets of the group and may be added to the totals of the items shown on the current group, 55 so as to display the exact condition of the

business at the time the current group is examined. A further object is to provide in such a group of account sheets or leaves what I term a master or control sheet whereon 60 may be entered under appropriate general classifications the various items carried in detail on the underlying sheet or sheets together with the aggregate or net amounts of such items properly distributed under 65 their appropriate headings on said master or control sheet. Still another object of the invention is to provide in such a group a convenient means of cross-reference between the control sheet and the underlying 70 detail or distribution sheets, so that items shown on either may be readily located and verified on the other.

Other objects and advantages of the invention will be apparent to those skilled in 75 the art from the following detailed description, taken in connection with the accompanying drawings, wherein I have illustrated one typical physical embodiment of the invention adapted to the uses of a commercial establishment comprising a number of different departments; the drawings showing a single group of sheets or leaves 80 designed to serve for a limited period and adapted for subsequent incorporation in 85 a loose-leaf binder. Referring to the drawings—

Figure 1 is a top plan view showing the several sheets of the group or set in superposed relation and temporarily held in such 90 relation by removable fasteners;

Fig. 2 is a top plan view of one of the intermediate sheets of the group which I term distribution or detail sheets, the particular sheet illustrated being the next to the 95 top sheet of Fig. 1;

Fig. 3 is a top plan view of the lowest or last sheet of the group, designed to record the trial balance and also certain other items of a general nature relating to the business 100 as a whole.

Referring to the drawings, 5 designates the top sheet of the group, 6, 6' and 6'' represent the intermediate or distribution sheets, and 7 the bottom or "general" sheet. 105 It will be noted that these several sheets are of increasing lengths in the order named, so that, when superposed with their top edges flush with each other a certain lower portion of each of the underlying sheets is 110 exposed to view.

The intermediate sheets 6, 6' and 6'', are

all alike functionally, and in Fig. 2 I have illustrated a sample detail sheet 6. In the instance shown, this sheet is divided by vertical lines 8 into a plurality of vertical columns 9 indicating different merchandise departments, and also certain other items classifiable under the general head of stock and storage. At the head and foot of each column are duplicate detail captions 10 designated by 10, each of these captions including a numeral which stands for the number of the column. Preferably, and as herein shown, these vertical columns are consecutively numbered throughout the entire group 15 of sheets, the numbering beginning with the columns on the uppermost or control sheet, and ending with the columns on the undermost or "general" sheet. At the left and right of the sheet are vertical columns 11 of consecutive numerals, each numeral designating a certain row or line extending lengthwise of the sheet. Where the entries are made by hand, the rows designated by these numerals are preferably separated by 20 horizontal parallel lines 12, as shown; although where the entries are made on a machine, these lines 12 may obviously be omitted, since the machine insures alinement and uniform spacing of the items. Just above 25 the lower captions 10 there is provided a ruled space 13 extending lengthwise of the sheet which is designed for the entry of figures denoting totals or aggregates from preceding sheets or groups, representing preceding time periods; and between the horizontal space 13 and the lower end of the columns 9 is a ruled space 14 extending lengthwise of the sheet in which may be entered the sums or totals of the individual 30 items entered in the several vertical columns 9. One or more of these intermediate detail or distribution sheets may be employed, according to the size and complexity of the business; it being understood that the sheets 35 6' and 6'' herein shown are functionally identical with the sheet 6 and are similarly ruled and spaced, differing from the latter only in the nature of the several items which they record.

40 The bottom sheet 7 is also a detail or distribution sheet, and is ruled and indexed in a manner generally similar to that of the intermediate sheets 6, 6' and 6''. It contains a single heading or caption 15 at the top and bottom denoted in the instance shown by the word "General," and also individual vertical column captions 16 at the top and bottom designating such general items as rent, salaries, capital, surplus, real estate and miscellaneous; while at the right of the sheet are debit and credit columns 17 and 18 respectively of a trial balance. At the left of the sheet is a vertical column 19 of consecutive numerals having the same function as 45 the columns 11 of the intermediate sheets,

while at the right is a similar vertical column 20, the numbers of which refer to the various column designating numerals which, in the instance shown, run from 1 to 40 inclusive. The sheet 7, like the sheet 6, is provided above the lower "General" caption 15 with a space 21 extending lengthwise of the sheet for the entry, in appropriate vertical columns of totals or aggregates from preceding sheets; and also, between the spacing 21 and the superposed numbered spacings, wherein detail items for the current period are entered, with a space 22 for the totals or aggregates of these detail items.

50 The control sheet 5 is ruled or spaced to provide at the left a vertical column 23 of sufficient width for the entry of various items of the business such as cash sales, charged sales, etc., which column preferably bears the caption "Items." To the right of the column 23 are a plurality of vertical columns 24 and 25 relating respectively to cash received and deposited; 26 and 27 relating to checks deposited in and drawn on the bank; 28 and 29 relating to merchandise paid for and received; and 30 and 31 relating to goods sold on credit and paid for on account. In the instance shown, these pairs of columns 24 to 31 inclusive are placed under the general captions of "Cash," "Bank," "Bought" and "Sold," being designated by the numerals 1, 2, 3 and 4 of the numeral column identifying indicia. At the left and right of this sheet are vertical columns 32 of consecutive numerals, these numerals serving to identify the general items which are entered thereagainst in column 23 with the specific items entered opposite the same numerals in the various columns of the intermediate sheets 6, 6' and 6''. To illustrate, there is entered opposite the numeral 3 on sheet 5 sundry bills mdse, \$150.00, the amount being entered in column 29 under goods bought and received. By reference to sheet 6, Fig. 2, it will be seen that this is the aggregate of 6 different specific items of goods bought by departments 1 to 6 inclusive, which items appear opposite the numeral 3 on sheet 6. Again, opposite the numeral 6 on the control sheet 5 is shown the entry "Paid sundry items, \$400.00," this last being entered in column 27, "Checks drawn." By reference to sheet 6, opposite the number 6 appear three specific items, pay roll \$40.00, expense paid \$5.00, freight paid \$5.00, aggregating \$50.00; and on sheets 6' and 6'' would be found other specific detail items paid by checks which would bring the total up to the \$400.00 shown in column 27 of the control sheet.

55 It will thus be seen that this master or control sheet 5 is made up from the detail entries on the underlying or distribution sheets and under appropriate headings and shows at a glance the totals or aggregates 60

- of the detail items on the distribution sheets. At the bottom of the columns 24 to 31 inclusive of the sheet 5 are spaces 33 in which are entered the totals of the columns; and 5 between the space 33 and the bottom caption of the sheet (which is a duplicate of the top caption) are similar blank spaces 34 for the entry of the aggregates shown by the preceding master or control sheets.
- 10 Hence by simply adding the current aggregates to the preceding aggregates the present condition of the several matters identified on the control sheet can be determined at a glance. By similar reference to the 15 current detail distribution sheet or sheets the exact condition of any single department or item of business may be ascertained at a glance. This capacity of the device of my present invention to show in what is 20 practically a bird's eye view, not only the general financial condition of the business but also the condition of any detail or department thereof constitutes one of the most valuable features of the present system.
- 25 The lower sheet 7 is designed and adapted for detail entries of specific items that relates to the business generally, rather than to any specific branch or department, such as rent, salaries of officers, capital, surplus 30 and real estate; and this sheet shows at the bottom the carried forward totals of similar preceding sheets from the first of the business year, so that by adding these totals to the totals on the current sheet, the 35 exact condition of the business as regards any of these general items is ascertainable at a glance. The specific items entered on the two sides of the trial balance in columns 17 and 18 are identified by the column numbers 40 on the superposed sheets. To illustrate, column 35 shows an entry of \$50.00 for rent paid and an entry of \$10.00 for salaries paid and these two entries appear opposite the numerals 35 and 36 on the debit 45 side of the trial balance. As hereinabove indicated, a group or set of sheets such as those herein shown and described is used for a given period of time which may vary from one day to one month or more according 50 to the extent and amount of business handled; and as soon as one group or set is filled, it may be filed away and a fresh group or set started, the totals or aggregates of the filled group being first entered at 55 the bottoms of the sheets of the new group so as to always enable the exact condition of the business generally and in detail, to be ascertained from the current group by a mere process of addition. This capacity of 60 the system is greatly facilitated by the structural peculiarity which consists in making the superposed sheets of different lengths so that the lower portion of each underlying sheet carrying the detail captions and the preceding totals or aggregates is visible at 65 a glance.
- To adapt the sheets or leaves to a loose leaf filing system, they are preferably notched or apertured at their upper edges, as shown at 35; and the several sheets of 70 a single group or set are preferably united by removable clips 36 applied to their upper edges. By simply curling or folding back any upper sheet, the entire matter on the next lower sheet may be brought to view. 75
- I claim:
1. An account book comprising a control or master sheet, and a distribution sheet underlying and projecting beyond the master sheet, said master sheet having columns designated for the entry of totals, and the distribution sheet having columns designated for the entry of the respective items comprising the respective totals on the master sheet, the projecting portion of the distribution sheet being provided with spaces designated for the entry of respective item totals. 80
  2. An account book comprising a control or master sheet, and a distribution sheet 90 underlying and projecting beyond the master sheet, said master sheet having columns designated for the entry of totals, and the distribution sheet having columns designated for the entry of the respective items 95 comprising the respective totals on the master sheet, each sheet having a series of numerals corresponding to the days of the month and common to the several entry columns, the projecting portion of the distribution sheet 100 being provided with spaces designated for the entry of respective item totals.
  3. An account book comprising a control or master sheet, and a distribution sheet underlying and projecting beyond the master sheet, said master sheet having columns provided with totals entry designations for the entry of totals, and the distribution sheet having columns provided with items entry designations for the entry of the respective items comprising the respective totals on the master sheet, each column of each sheet having identical entry designations at the top and bottom thereof, each sheet having a series of numerals 110 corresponding to the days of the month and common to the several entry columns, the projecting portion of the distribution sheet being provided with spaces 115 having entry designations for the entry of respective item totals.
  4. An account book comprising a plurality of sheets disposed one upon the other and projecting progressively at the bottom edge of the book from the uppermost to the lowermost sheet, each sheet being provided with a plurality of upright columns extending to the bottom of the sheet and 125

provided with entry designations and each column being provided at its top and bottom with identical entry designations.

5. An account book comprising a plurality of sheets disposed one upon the other and progressively projecting at their bottom edges from the top to the bottom of the book, each sheet being provided with a plurality of upright columns extending to the bottom of the sheet, an upright series of numerals corresponding to the days of the month and common to the several columns, and each column being provided at its top and bottom with identical entry designations.

6. An account book comprising a control or master sheet, and a distribution sheet underlying and projecting beyond the master sheet, said master sheet having columns designated for the entry of totals, and the distribution sheet having columns designated for the entry of the respective items comprising the respective totals on the master sheet, the projecting portion of the distribution sheet being provided with spaces designated for the entry of respective item

totals, and the columns of the sheets being successively designated.

7. An account book comprising a control or master sheet provided with a plurality of upright columns having totals entry designations at the tops and bottoms thereof, the designations at the top and bottom of each column being identical, an upright series of numerals at the left of the sheet and an identical upright series of numerals at the right of the sheet, each series beginning at the top with the numeral 1, and a distribution sheet beneath the master sheet and projecting below the bottom of said master sheet, said distribution sheet having a plurality of upright columns extending to the bottom of the sheet and provided with items entry designations, the designations at the top and bottom of each column being identical, there being an upright series of numerals at the left of the distribution sheet and an identical series of numerals at the right of said sheet, each series beginning at the top with the numeral 1, and the columns of both sheets being successively designated.

DAVID R. JONES, JR.
